T. H. SCHROR ET AL

GAME

Filed Sept. 12, 1922

Fig. 1.

Fig. 2.

UNITED STATES PATENT OFFICE.

THEODORE H. SCHROR AND GEORGE L. SCHROR, OF ALBION, NEW YORK.

GAME.

Application filed September 12, 1922. Serial No. 587,697.

To all whom it may concern:

Be it known that we, THEODORE H. SCHROR and GEORGE L. SCHROR, citizens of the United States, residing at Albion, in 5 the county of Orleans, State of New York, have invented a new and useful Game; and we do hereby declare the following to be a full, clear, and exact description of the invention, such as will enable others skilled in 10 the art to which it appertains to make and use the same.

The invention relates to games of the checkered surface type and has for its object to provide a game of this character 15 having a plurality of adjacent spaces in transverse alignment at right angles to each other and a plurality of discs for opposing players, each player positioning the discs on the board with the object of preventing the 20 opposing player from placing discs transversely of the board in alignment.

With the above and other objects in view the invention resides in the combination and arrangement of parts as hereinafter set 25 forth, shown in the drawing, described and claimed, it being understood that changes in the precise embodiment of the invention may be made within the scope of what is 30 claimed without departing from the spirit of the invention.

In the drawing:—

Figure 1 is a plan view of the game board.

Figure 2 is a perspective view of the game board showing the same folded.

Figure 3 is a perspective view of two of the discs, which discs are of different color.

Referring to the drawing, the numeral 1 designates a rectangular shaped game board which is preferably formed from two sections 2, which are hingedly connected together at 3, thereby allowing the board to be stored when not in use. The board is provided with a plurality of spaces 4, which spaces are in alignment at right angles, 40 thereby allowing a plurality of discs 5 and 6 to be placed on the spaces 4 in such a man-

ner that they will be in alignment at right angles to each other. The discs 5 and 6 of opposing players are differently colored, and the players alternately place discs on 50 the spaces 4 with the object of securing a straight line of discs extending across the board, and in such a manner as to block the other player from securing a straight line of discs. The alignment of the discs is transversely of the board and not diagonal, for 55 instance from A to B, D to C or B to A, or A¹ to B¹. It will be noted that each player plays at a right angle with the object of securing a straight line of discs at a right 60 angle to the direction of play of the opponent. The player who first secures a straight line of discs extending entirely across the board wins the game.

The board transversely is provided with 65 six spaces and as each player is provided with ten discs, it is obvious that considerable maneuvering may be done in an attempt to block each opponent against securing a straight line of discs across the 70 board.

The invention having been set forth what is claimed as new and useful is:—

A game comprising a game board, a plurality of spaces carried by the game board, 75 said spaces being six in alignment at right angles and adapted to receive ten discs, said discs being adapted to be aligned by opposing players, with the object of securing a straight line of six discs entirely across the 80 board at a right angle to the direction of play of opponent without being blocked by the opposing player, said players playing at right angles to each other.

In testimony whereof we have signed our 85 names to this specification in the presence of two subscribing witnesses.

THEODORE H. SCHROR,
GEORGE L. SCHROR.
